GAME APPARATUS

William Alexander Glover, Chattanooga, Tenn.,
and Addie Sue Wimberly, Rome, Ga.

Application April 9, 1940, Serial No. 328,746

10 Claims. (Cl. 273—96)

The present invention relates to new and useful improvements in a game apparatus, and more particularly to improvements in an implement for playing games of the type employing some form of game-piece which is adapted to be moved toward and away from a player.

There are several types of games which contemplate the movement of some form of game-piece between opposing players. In tennis, for instance, a ball is propelled by manipulation of a racket between opposing players on opposite sides of a suitably marked court which is divided into opposing zones by a net. The ball may be hit during its original trajectory, or after a single bounce. In badminton, on the other hand, the shuttle, or "bird," is hit only during its original flight. There are other types of games, such as squash, wherein one or more marked walls are employed and against which the game-piece may be directed.

According to the present invention, the game-piece is preferably in the form of a ball which is adapted to be propelled and caught by manipulation of the game implement. The ball may be projected against a wall board and caught on the rebound by the same or another player, but the invention particularly contemplates the projecting of the ball by one player and the catching of the ball by an opposing player. Each player has a game implement which can be manipulated in one hand, and this implement includes a receptacle for catching the ball and a projecting mechanism for starting the ball on its flight. A line or net may be employed for dividing the playing surface into opposing zones which may, if desired, be sub-divided in various ways. The ball is to be propelled by operation of the projecting means on the implement by one player into an opposing zone where it is to be caught on proper manipulation of the implement by another player. Various rules may be drawn for playing such a game, but it is contemplated that the ball may be caught on its original trajectory, or on its first bounce. Differential scoring may be devised for such variations. If the opposing player fails to catch the ball with the implement, the opposing player is entitled to a predetermined score.

An object of the invention is to provide a game implement of the above type which includes a flexible and reversible receptacle so as to permit the ball to be caught in various positions of the implement, and which also includes a ball projecting mechanism which is manipulated by the player.

A further object of the invention is to provide a game implement of the above type wherein the projecting mechanism is in the form of a catapult and may be cocked and released by finger manipulation of the player.

A further object of the invention is to provide a game implement of the above type wherein the catapult means includes a ball holding device which is constructed so as to permit the ball to be releasably maintained therein, thus permitting the implement to be aimed at any angle.

A further object of the invention is to provide a game implement of the above type having a ring member disposed substantially in the plane 15 of the implement handle for supporting the flexible netted receptacle, and wherein the catapult means is movable substantially in line with the handle and in a plane at right angles to the plane of the ring member whereby to permit the 20 game-piece to be aimed by aiming of the implement.

The above and other objects of the invention will in part be obvious and will be hereinafter more fully pointed out.

25 In the accompanying drawing,

Figure 1 is a perspective view of the game implement with the projecting mechanism and ball in cocked position.

Figure 2 is an enlarged fragmentary side view, 30 in section, showing the game implement of Figure 1, but showing the position of the projecting mechanism after the ball is released in dotted lines.

Figure 3 is a sectional view taken along the line 3—3 of Figure 2 showing the ball holding means on the projecting mechanism.

Referring more in detail to the accompanying drawing, the game implement includes a handle 10 which may be grasped by the hand H of the player. The forward end of the handle 10 has imbedded therein and secured thereto the leg portions 11, 11a of a wire member which includes a forwardly spaced ring portion 12. A reinforcing ring member 13, coincidental with the ring portion 12, is secured adjacent thereto by a substantially S-shaped clamping member 14. The ring portion 12 and the ring member 13 are made from wire stock and thus cooperate with one another for strengthening purposes. Secured around the clamping member 14 are the strands 15 of a flexible net 16 which provides a flexible receptacle for catching the ball B, or other game-piece. The flexible netted receptacle 16 is reversible 45 through the ring members so that the game-piece or ball may be caught in various positions

50

55

of the implement. A thimble 17 is secured over the forward end of the handle portion 10.

The leg portions 11, 11a of the ring portion 12 are disposed next to one another where they are secured to the handle portion 10, and these leg portions are disposed substantially next to one another where the ring portion 12 begins. However, the intermediate portions 18, 18a of the leg portions 11, 11a, respectively, are spaced apart and form a substantially diamond-shaped guide portion for the projecting mechanism. This projecting mechanism preferably includes a bent leaf spring 19 which is secured to the bottom face of the handle 10 by means of bolts 20 and nuts 21. The heads of the bolts 20 may be disposed in countersunk recesses 22 in the upper face of the handle 10 so that the handle will present a smooth surface to the player's hand. The nuts 21 on the bottom face of the handle 10 may also be countersunk and the spring member 19 accordingly shaped, if so desired. However, when the nuts 21 are exposed, they serve as finger gripping means for the player. The end 19a of the spring member 19 is imbedded in the handle 10 which may be made of wood or the like.

The free end 23 of the leaf spring 19 is bent upon itself to provide a rounded bead which serves as a thumb gripping surface for setting or cocking the projecting mechanism. Between the free end of the spring 19 and the curved portion 19b thereof, a ball holding device 24 is mounted. The ball holding device is preferably formed from sheet metal and includes a base portion 25 which is secured to the spring member 19 adjacent the free end 23 thereof by means of a bolt 26 or the like. A part of the base portion 25 on each side of the spring member 19 is cut and bent beneath the edges of the spring member so as to provide holding lugs 27, 27a. The holding device is substantially circular in shape and includes at the forward end thereof a relatively high upstanding wall portion 28. The forward wall portion 28 is reduced in height to provide curved side portions 29, 29a which merge into a relatively short rear end portion 30. The edge of the front wall portion 28 and the side wall portions 29, 29a are turned inwardly to provide a holding flange 31. Thus, the ball B which is slightly resilient may be lightly pressed into the holding device and held therein by engagement of the flange 31 therewith. Thus, the implement can be turned through any angle without the ball dropping out of the holding device. The gradual reduction of the height of the wall portions 29, 29a toward the rear of the holding device is for the purpose of permitting the ball to be projected therefrom without interference when the projecting mechanism is released.

In operation, the ball B is lightly pressed into the holding device 24 within the recess formed by the wall portions 28, 29, 29a, 30, so that the flange 31 will lightly hold the ball in this position. The projecting mechanism, which is in the form of a catapult, is cocked or set to the position shown in full lines in Figures 1 and 2 with the thumb of the player's hand engaging the free end 23. In this position of the device, the player can aim the implement and a slight alteration of this aim is permitted by laterally moving the leaf spring 19 by the thumb. Upon releasing the free end 23 of the catapult spring 19, the spring and holding device will assume the position shown in dotted lines in Figure 2, and the ball B will be released from the holding de-

vice. The opposing player is then called upon to catch the projected ball in the net receptacle 16, and for this purpose, the implement can be turned to any position and the flexible nature of the net receptacle will permit the ball to become lodged therein. As indicated above, suitable scoring methods may be devised and the initial projecting or serving of the ball can be altered according to the various rules.

It will be seen that the ring supporting members 12, 13 for the net receptacle 10 are disposed substantially in a plane with the straight handle portion 10. The catapult spring also moves substantially in a plane with the handle portion 10. However, this latter plane of movement of the spring 19 is disposed at substantially right angles to the plane of the receptacle supporting ring. The spring 19 is guided to a limited extent by the outwardly bent leg portions 18, 18a which also serve to limit forward movement of the spring when released, thus preventing the projecting mechanism from discharging the ball into the net of the same implement through its ring support. The movement of the spring 19 in a plane substantially at right angles to the plane of the net supporting ring and the limiting stop for the spring assure proper projection of the ball without interference from the net or its supporting member.

While one form of the invention has been shown for purposes of illustration, it is to be clearly understood that minor changes in the details of construction and arrangement of parts may be made without departing from the scope of the invention as set forth in the appended claims.

We claim:

1. A game implement comprising a handle, a supporting ring having leg portions secured to said handle, said leg portions being outwardly bent intermediate the ends thereof, a net carried by said supporting ring for catching a projected game-piece, a flat spring having one end thereof secured to said handle and having the free end 40 thereof extending between the outwardly bent leg portions, and means carried adjacent the free end of said spring for holding a game-piece whereby to permit setting and releasing of the spring to effect projection of the game-piece.

2. A game implement comprising a handle, a supporting ring having leg portions secured to said handle, said leg portions being bent outwardly intermediate the ends thereof, a net carried by said supporting ring for catching a projected game-piece, a bent spring having one end thereof secured to said handle and having the free end thereof extending between the outwardly bent leg portions and adapted to strike against the forward portion of said leg portions when released whereby to provide a limiting stop, and means carried adjacent the free end of said spring for holding a game-piece whereby to permit setting and releasing of the spring to effect projection of the game-piece.

3. In a game implement for projecting and catching a game-piece and including a handle and a game-piece catching device, the combination with said handle of a game-piece projecting mechanism releasable toward said catching device, and means independent of said projecting mechanism and located between said handle and said catching device for preventing said projecting mechanism from extending over the receiving end of said catching device when the projecting mechanism is released.

4. In a game implement for projecting and catching a game-piece, the combination of a handle, a game-piece catching device secured to the handle immediately adjacent one end thereof, a game-piece projecting mechanism carried by the handle close to the catching device and movable in a plane substantially at right angles to the plane of the said catching device and substantially in line with said handle whereby to permit aiming of the game-piece, and means for preventing said projecting mechanism from extending over the receiving end of said catching device when the projecting mechanism is released.

5. In a game implement for projecting and catching a game-piece, the combination of a handle, a game-piece catching device, means for securing the catching device to one end of said handle, a game-piece projecting mechanism carried by the handle, and means associated with the securing means between the catching device and the handle for preventing the projecting mechanism from extending over the receiving end of said catching device when the projecting mechanism is released.

6. A game-piece implement comprising a handle, a supporting ring for a catching device, said ring having spaced leg portions secured to said handle, a spring having one end thereof secured to said handle and having the free end thereof extending between said leg portions, and means carried adjacent the free end of said spring for holding a game-piece whereby to permit setting and releasing of the spring to effect projection of the game-piece.

7. A game implement for projecting and catching a game-piece, comprising a holding member carried by said handle and adapted to support a catching device, a game-piece projecting mechanism carried by said handle, and means located between said member and said handle and cooperating with said projecting mechanism for guiding the said projecting mechanism and for preventing the same from extending over the receiving end of the catching device when released whereby to prevent interference with the free use of the catching device.

8. A game implement for projecting and catch-

ing a game-piece, comprising a handle carrying a game-piece catching device, a game-piece projecting mechanism releasable toward said catching device, and a recessed holder carried by said projecting mechanism and having inwardly directed flange means for gripping the game-piece during movement of the projecting mechanism toward a set position whereby to prevent accidental displacement of the game-piece prior to projection thereof.

9. A game implement for projecting and catching a game-piece, comprising a handle carrying a game-piece catching device, a game-piece projecting mechanism carried by said handle and adapted to be shifted to a set position away from said catching device, a substantially cylindrical holder mounted adjacent the free end of said projecting mechanism for holding the game-piece during shifting of the projecting mechanism to a set position whereby to prevent accidental displacement of the game-piece prior to projection thereof, and the wall portion of said holder being reduced in height toward the rear of said projecting mechanism when in set position whereby to facilitate release of the game-piece when the projecting mechanism is released from its set position.

10. A game implement for projecting and catching a game-piece, comprising a handle carrying a game-piece catching device, a bent spring having one end thereof secured to said handle with the free end thereof extending forwardly of said handle toward said catching device and adapted to be pulled back into set position, a substantially cylindrical holder mounted adjacent the free end of said spring, flange means extending inwardly from a portion of said holder for gripping the game-piece during movement of the spring to its set position whereby to prevent accidental displacement of the game-piece prior to projection thereof, and the wall portion of said holder being reduced in height toward the free end of said spring when in set position whereby to facilitate release of the game-piece when the spring is released from the said set position.
